(57) CLAIM

The ornamental design for a mattress with contrasting tape edge and handles, as shown and described.

DESCRIPTION

FIG. 1 is a perspective view of a first embodiment of the mattress with contrasting tape edge and handles.

FIG. 2 is a side view of the mattress with contrasting tape edge and handles of FIG. 1, identical to the opposite side thereof. FIG. 3 is an end view of the mattress with contrasting tape edge and handles of FIG. 1, identical to the opposite end thereof.

FIG. 4 is a top view of the mattress with contrasting tape edge and handles of FIG. 1.

FIG. 5 is a bottom view of the mattress with contrasting tape edge and handles of FIG. 1.

FIG. 6 is a perspective view of a second embodiment of the mattress with contrasting tape edge and handles.

FIG. 7 is a side view of the mattress with contrasting tape edge and handles of FIG. 6, identical to the opposite side thereof. FIG. 8 is an end view of the mattress with contrasting tape edge and handles of FIG. 6, identical to the opposite end thereof.

FIG. 9 is a top view of the mattress with contrasting tape edge and handles of FIG. 6; and,

FIG. 10 is a bottom view of the mattress with contrasting tape edge and handles of FIG. 6.

The light stipple shading in the first embodiment and the heavy stipple shading in the second embodiment represent a contrast in appearance relative to the rest of the mattress.

The broken lines are for environmental purposes only and form no part of the claimed design.
